UNITED STATES PATENT OFFICE.

ADELINE M. WALKER, OF ELIZABETH, NEW JERSEY.

DESIGN FOR A DOLL.

52,713.

Specification for Design.

Patented Nov. 19, 1918.

Application filed May 23, 1918. Serial No. 236,233. Term of patent 7 years.

To all whom it may concern:

Be it known that I, ADELINE M. WALKER, a citizen of the United States, residing at Elizabeth, in the county of Union and State of New Jersey, have invented a new, original, and ornamental Design for a Doll, of which the following is a specification, reference being had to the accompanying drawing, forming part thereof.

The figure is a perspective view of a doll showing my new design.

I claim:

The ornamental design for a doll as shown.

ADELINE M. WALKER.
